DESIGN FOR A SQUEEGEE OR SIMILAR ARTICLE

John R. Oishei, Buffalo, N. Y., assignor to Trico Products Corporation, Buffalo, N. Y.

Application January 21, 1936, Serial No. 60,709

Term of patent 7 years

To all whom it may concern:

Be it known that I, John R. Oishei, a citizen of the United States, residing at Buffalo, in the county of Erie and State of New York, have invented a new, original, and ornamental Design for a Squeegee or Similar Article, of which the following is a specification, reference being had to the accompanying drawing, forming part thereof.

Fig. 1 is a perspective view of a squeegee or similar article showing my new design, the features shown complete therein being repeated throughout the length of the article within the border lines indicated; and

Fig. 2 is a cross sectional view of the squeegee.

I claim:

The ornamental design for a squeegee or similar article, as shown and described.

JOHN R. OISHEI.
